(57) **CLAIM**

The ornamental design for a hair dryer, as shown and described.

DESCRIPTION

1. Hair dryer
1.1 is a perspective view showing the hair dryer of my design;
1.2 is a front elevational view thereof;
1.3 is a rear elevational view thereof;
1.4 is a right side elevational view thereof;
1.5 is a left side elevational view thereof;
1.6 is a top plan view thereof;
1.7 is a bottom view thereof;
1.8 is a bottom view thereof as 1.7 showing a portion of the hair dryer encircled; and
1.9 is an enlargement of the encircled portion of the hair dryer of 1.8.
The broken lines are depicting internal elements of the hair dryer are for environmental purposes only and form no part of the claimed design.
